United States Patent Office.

THOMAS M. MOORE, OF NEWTON, NEW JERSEY.

Letters Patent No. 77,398, dated April 28, 1868.

IMPROVED CAR-COUPING.

The Schedule referred to in these Letters Patent and making part of the same.

TO ALL WHOM IT MAY CONCERN:

Be it known that I, THOMAS M. MOORE, of Newton, county of Sussex, and State of New Jersey, have invented certain new and useful Improvements in "Car-Couplings;" and do hereby declare that the following is a full, clear, and exact description thereof, reference being had to the accompanying drawings, and to the letters of reference marked thereon, making a part of this specification.

The nature of my invention consists in the construction of the car-coupling in such a manner that it may be easily and readily detached from the car whenever so desired; for instance, when one car is thrown from the track.

The front portion of my car-coupling, together with the coupling-link and pin, is of the usual and ordinary construction. The connection of the coupling to the car is such that it cannot be disengaged from the car unless it is twisted partially around, as will be described.

In the annexed drawings, *i* represents the front of the coupler, in the rear of which is the usual recess, within which the link lies, where it is secured by the pin *l*.

The forward end of the coupling is rounded at the sides, (as seen in Figure 2,) from the rear of which, at the centre, extends a metal plate, *d*, which is placed vertically, and is provided with a notch on its upper and lower sides. This plate is passed into a sliding metal box *j*, which is secured on the under side of the car by keepers, or in any other suitable manner.

The box *j* is open at each side and at its front end, at which latter point there are two lugs or projections, *c c*, that fit into the notches in the plate *d*. Within the box *j* there is a pivoted plate, *f*, fig. 2, having a suitable slot, and into which passes the end of the plate *d*. Around this pivoted plate is a hoop-spring, *k*, that keeps it in position.

From the rear of the box is a rod, having a rubber spring, *a*, so that whenever the sliding box is forced to the rear by the opposite car, this spring will throw the coupler back into position.

It will be seen that whenever the coupling is drawn too far on either side, the plate *d* will be released from the projections *c c* in the box *j*, and can be extracted from the car. As the same is partially turned, the plate *f* turns upon its pivot, and as the pressure is withdrawn, the spring *k* will carry the same in its proper place again.

Having thus fully described my invention, what I claim as new, and desire to secure by Letters Patent, is—

The arrangement of the notched plate *d* on the rear of the head *m*, in combination with the sliding box *j*, with its projections *c c*, and interior pivoted plate *f*, and spring *k*, all constructed and operating substantially as specified.
